UNITED STATES PATENT OFFICE.

WILLIAM H. VIOLETT, OF GRAND JUNCTION, COLORADO.

POOL-TABLE.

SPECIFICATION forming part of Letters Patent No. 451,536, dated May 5, 1891.

Application filed July 5, 1890. Serial No. 357,910. (No model.)

To all whom it may concern:

Be it known that I, WILLIAM H. VIOLETT, residing at Grand Junction, in the county of Mesa and State of Colorado, have invented 5 certain new and useful Improvements in Pool-Tables, of which the following is a specification.

My invention relates more particularly to improvements on the table shown and described in another application filed by me June 19, 1889, Serial No. 314,877; and it has for its object to simplify the construction thereof, render the operation more positive, and to provide suitable means whereby any 15 single one or all the balls can be removed from the several pockets, and whereby the cue-ball may be deflected to the side of the table, where the player who made the shot is standing.

20 My invention consists in the peculiar combination and novel arrangement of the several parts, all of which will hereinafter be described in the annexed specification, and particularly pointed out in the claims, reference 25 being had to the accompanying drawings, in which—

Figure 1 is a side view of my improved pool-table. Fig. 2 is a top plan view thereof, the table proper being shown in dotted lines. 30 Fig. 3 is a view of the "rack" end of the table. Fig. 4 is a similar view of a portion of the opposite end. Figs. 5 and 6 are detail views illustrating one of the sliding gates and cut-off connected to each of the pockets. Figs. 35 7 and 8 illustrate in detail the means for shifting the cue or scratch ball. Fig. 9 is an inverted plan view of the device shown in Fig. 7. Fig. 10 is a bottom plan view of the gong-operating devices.

40 One of the established rules in the game of pool is, that if a player pockets the cue-ball he forfeits one of his balls out of the rack and spots it on the table again. In my other application referred to I did not provide means for getting the scratch-ball out of the series of troughs or pockets forming said rack without letting all the balls of the particular trough or pocket fall out.

45 In the drawings, A indicates the table, which is provided with the usual corner and side pockets $a a'$, which open into the car-

riers or tubes B B, which lead into a single trough B² at a point under the center of the table, supplemental carrier-tubes B' being provided at the side pockets, which deflect 55 the balls from a direct discharge from such side pockets and prevent the balls from entering the trough B² too rapidly.

C indicates an inclined swinging switch which serves to lead the balls from the end 60 of the trough B² into any one of a series of troughs or pockets D', preferably eight in number, such number of players being the largest that can enter into the game. The upper end of the switch-trough is always in 65 communication with the discharge end of the trough B².

E indicates the switch-operating lever which runs from one end of the table to the other under it, its free end e projecting sufficiently to allow plenty of room to move it laterally under an indicator-plate f, which is divided into eight divisions, indicating the numbers of the troughs or pockets of which the rack D proper is composed. Thus, should 75 a player whose number is 7 play, he would, after he has made his shots, shift the end e of the lever E under 7, which would shift the switch C to connect the trough B² with trough 80 No. 7.

The bar E is pivoted below the center of the table on a transverse bar I, and is connected to the switch C at the point j by means of a pin k, formed on brackets k' k', projected from the switch C, said pin entering a slot j' 85 in the bar E, as shown, the end e' of the bar being projected over the rack D, so the same can be shifted from either end of the table.

The rack D consists of a series of longitudinal troughs D', the outer ends of which are 90 closed by spring-actuated slides d, one of which is shown in detail in Figs. 5 and 6 of the drawings, by reference to which it will be seen that vertical guideways d' d' are formed on the outer faces of the troughs D', in which the slides operate, each of such slides being formed with a cut-off d², as shown. By this construction it will be observed that when it is desired to take out a ball to be spotted on the table the player pushes the slide down to 95 the position shown in dotted lines in Fig. 6. This allows the first ball to roll out. The cut-

off d^2 , however, coming down in front of the next succeeding ball, will hold it in the trough.

To provide means whereby the slides will be automatically closed and held closed, I employ the device shown in Figs. 3 and 5, which show a spring 10, to which is attached one end of a cord 11, which is secured at its opposite end to a lug or pin b . Said cord passes over a series of pulleys 12, arranged one intermediate each slide d . The lower end of each of the slides is provided with a grooved roller 13, which rests upon the cord, as shown. By this construction it will be seen that when any one of the slides is pulled down it will press the cord down, drawing on the tension of the spring, and when the slide is released the spring will quickly draw the cord up and move the slide over the discharge-opening of the respective trough D' .

20 G denotes the switch-gate, which serves the double purpose of allowing the balls to enter the trough B^2 and also to deflect the scratch or cue ball to be discharged at either side of the machine. By reference to Figs. 2, 6, and 25 7, which show said device and its adjuncts most clearly, it will be seen that the same consists of the transverse trough-sections G' G^2 , which are arranged transversely to the trough or chute B^2 and disposed below the same, said 30 troughs G' G^2 at their intersection with said trough B^2 being provided with a slide 20, which projects up and forms the bottom of the chute or trough B^2 at this point, said slide being connected with a lever F, pivoted at F' , to 35 the front end of which is connected the ends of oppositely-extending cords g g' , which project up under the table near the side pockets. By this arrangement, in case the cue-ball enters any of the pockets the player, by pulling 40 the cord nearest him, will cause the lug to be moved by means of the lever F, so the ball will drop into the trough G' or G^2 and roll out toward him into a basket X, and as the player releases the cord the spring f^3 will 45 pull the lever F and the slide 20 back to their normal position.

U denotes the gate for closing the chute B^2 , which in the present case is placed at a point marked V on the drawings, being in advance 50 of the transverse trough G. This gate is operated in the following manner: Under each end of the lever E, near the center of the hinged bar l , is fastened a cord L, which passes up over four small stationary pulleys m n , the pulley n being near the center of the lever E, and the pulley m near the ends thereof. Directly under the pulleys n n is arranged a pulley o, and to the left of the same, over the gate U, is another pulley p. The cords L 55 pass down under the pulley o, over the pulley p, and are connected to the gate U, as shown.

When a player is through playing, he shoves the lever E (from either end of the table) to 60 bring the switch to his particular trough D' , and by pressing down on either of the bars l , (see dotted lines, Fig. 1,) he will draw upon

the cord L, thereby raise the gate U and allow all the balls held in the chute B^2 to pass into his rack.

The object of placing the pulleys n n and o near the center, as shown, is to allow for the moving of the lever E without drawing on the cord L.

If desired, the lever E may be made to come 75 through the end of the table at or near the dotted line r and still be operated on the same principle.

A sliding plate e^5 engages with a spring-actuated hammer f^3 , adapted to ring a gong g^5 , 80 a spring h^5 being employed to pull the plate to its normal position. By this arrangement each time the switch is moved notice of such movement will be given by means of the gong g^5 .

i^5 indicates a cord which is connected with the cord 11, said cord i^5 being passed through suitable guides j^5 and held in such a manner that when any of the slides d are pulled down the gong g^5 will be caused to ring. When the 90 game is finished and the balls are again wanted to put back onto the table, a lever H^5 , which is pivoted at one end, is drawn back by its handle, and said lever being pivoted to a slide I^5 , which covers holes o^5 in the bottoms of the 95 lower end of each trough D' , will pull said slide from under the said holes o^5 , and allow the balls to roll into a chute C^5 and be discharged therefrom into a basket F^5 . On one 100 end of the lever H^5 is secured a finger K^5 , which engages a spring-plate m^5 , with which is connected one terminal of an electrical circuit, the other terminal ending with a parallel plate n^5 , a suitably-arranged alarm-bell being located in said circuit, preferably within earshot of the attendant or proprietor of the 105 billiard and pool parlor.

As the lever H^5 is moved, as described, the two plates m^5 and n^5 will come into contact and thereby close the circuit and ring the 110 alarm, thereby notifying the proprietor or attendant, even if located in another room, that a game has been finished and a new one about to be commenced. In connection with the lever any suitable registering devices 115 may be employed, whereby the number of games played will be recorded.

From the foregoing description, taken in connection with the drawings, the advantages of my improved pool-table will readily appear. 120 It will be seen that the players have full control of the balls, and the necessity of traveling across the room and walking about the table to take the balls out of the pockets and place them in the racks usually employed is 125 entirely avoided.

Having thus described my invention, what I claim, and desire to secure by Letters Patent, is—

1. The combination, with the table, the 130 chute or trough B^2 , and the chutes B B' intermediate the table-pockets and the trough B^2 , of a series of troughs D' , a swinging switch or independent trough C, adapted to connect

the trough B² with any one of the troughs D', and a lever centrally pivoted under the table and extended to the ends thereof and connected with the switch C, whereby the same will be 5 shifted as the lever is swung on its pivot, substantially as and for the purpose described.

2. In a pool-table essentially as described, the combination, with the table, the chute B², the chutes B' B', connecting said chute with 10 the pool-table pockets, and a series of troughs or pockets D', located below the table, of a supplemental pivoted switch-trough C, adapted to connect the chute B² and any one of the troughs D', the cut-off gate U in the chute B², 15 the centrally-pivoted lever E, and the operating-cords L L, located on the lever and connected with the gate U, said lever connected with the switch-trough C and adapted to swing the same, substantially as and for the purpose 20 described.

3. In a pool-table essentially as described, the combination, with the table, the chute B², the chutes B' B', connecting the chute B² with the table-pockets, and a cut-off slide U, held 25 in the chute B², of the transverse troughs G' G² and a device consisting of the slide 20 and the swinging lever F, said slide 20 adapted to normally form a bottom portion of the trough B² and to deflect the balls and allow 30 them to roll out in either of the troughs G' G² when swung by the lever F, substantially as and for the purpose described.

4. In a pool-table essentially as described, the combination, with the table, the chutes 35 B' B', connected with the table-pockets, and the chute B², of a series of troughs D', held below the table, a switch-trough adapted to deflect the balls from said chute B² to any of the troughs D', a cut-off gate U, held in said 40 chute B², transverse troughs G' G², communicating with the chute B² in advance of the gate U, a shifting slide or gate operating at the juncture of the troughs G' G² and chute B², and means for operating the slide where- 45 by the balls may be deflected and discharged to either side of the table, substantially as and for the purpose described.

5. In a pool-table essentially as described, the combination, with the table, the chute B², 50 the chutes B' B', connecting said chute B² with the table-pockets, and a series of troughs D', located below the table near one end, of a

swinging trough or switch C, adapted to be adjusted to connect the chute B² with any one of the troughs D', an indicator-plate located 55 at the end of the table opposite the troughs D', and a centrally-pivoted lever E, connected with the swinging trough or switch C, its front end projected under the indicator-plate, all arranged substantially as and for the purpose described.

6. In a pool-table essentially as described, the combination, with a series of troughs D' D', located below the table and communicating with the pockets thereof, of a series of 65 sliding gates, each formed with a cut-off, said gate adapted when lowered to allow the first ball to fall out, the cut-off adapted to come in front of the next succeeding ball and hold same in position, substantially as and for the 70 purpose described.

7. The combination, with the table and the troughs D', located below the same and communicating with the pockets thereof, of the sliding gates held over the discharge end of 75 such troughs, and devices for automatically holding all of said gates in a closed position and arranged to close them when opened by hand, substantially as and for the purpose 80 described.

8. The combination, with the troughs D' and the sliding gates held to automatically close said troughs D', of the spring-tension cord located beneath said gates to hold them closed, a gong located on the racks, and in- 85 termediate connections between said gong and the cord whereby said gong is sounded when any one of the gates is depressed, substantially as and for the purpose described.

9. In combination with the troughs D', 90 formed each with a discharge-opening in the bottom near the ends thereof, communicating with a single chute, a cut-off slide I', adapted to normally close said openings, an electrical circuit, and an alarm-bell in said circuit, said 95 circuit adapted to be closed when the slide I' is shifted from under said openings, all arranged substantially as and for the purposes described.
